APPARATUS FOR PLACING WRAPPERS ON
THE ROLLING APRON OF A CIGAR ROLL-
ING DEVICEFranz Heinrich Benno Stelzer, Dresden, Ger-
many, assignor to "Universelle" Cigaretten-
maschinen-Fabrik J. C. Müller & Co., Dresden,
GermanyApplication November 30, 1932, Serial No. 645,087
In Germany December 15, 1931

33 Claims. (Cl. 131—42)

In cigar rolling apparatus of the apron-rolling type and in which the portion of tobacco allotted for making the filler is thrust into a trough on the rolling table on which the rolling apron is located, a roller extending over the table co-operates with the rolling apron for the purpose of forming the bunch. This roller is mounted on a suitably pivotally mounted lever support. In the preparation of a bunch the tobacco is provided with a wrapper. This must therefore be placed on the rolling apron, which is generally done by hand. As the wrapper must first of all be prepared (spread out and smoothed) before it can be applied, there is a relatively short time available for this operation which must be performed by one and the same person, and consequently the attendant does not allow the machine to run continuously, but stops it whenever a wrapper has to be applied and sets it in motion again when the operation is completed. With large plants of complicated construction, the wrapper-applying operation can be performed by purely mechanical means, for instance by means of a suction head which seizes the wrapper which is cut out on a table, likewise mechanically, and then is guided in such manner that it forwards the wrapper to the depositing position. This, however, is an apparatus of very complicated construction and above all very expensive, because the control of the suction head is not simple and at the same time a means of control of the suction air current itself must be provided.

The object of the present invention is to apply the wrapper by purely mechanical means while using machines of simple construction, i. e. small cigar-making machines.

This end is attained by providing the rolling apparatus with a special table on which the wrapper is placed in such manner that a controlled gripping member arranged on the support of the bunch roller, on the forward movement of the support, seizes the wrapper and on its backward movement, places it over the trough which receives the filler tobacco.

In this manner the support of the bunch roller itself is utilized for applying the wrapper, so that by means of this already available swinging member the wrapper can be applied mechanically without other intermediate members being provided, namely with ease, at the right moment and at the right place.

The invention is illustrated in the annexed drawings, in which:—

Fig. 1 is a vertical longitudinal section through the apparatus.

Fig. 2 is a similar view in another operative position.

Fig. 3 is a partial plan.

Fig. 4 is a vertical section on the line 4—4 of Fig. 3.

Fig. 5 shows the parts of the apparatus illustrated in Fig. 4 in another operative position.

Figs. 6—11 are detailed views.

The table 1 for the wrapper consists of a plate provided with sieve-like openings beneath which a suction head housing 2 is mounted. The suction head housing is connected by means of a pipe 3 with a fan 4 which is driven by a belt 5 and a motor 6. The suction head housing is carried by a projecting arm G' attached to the machine frame G. The table 1, the special form of which is shown in Fig. 3, is provided with four recesses 1' in which the hereinafter described gripping members engage. The gripping members consist of a bar 7, which is carried by two arms 8. The latter are carried on levers 10 mounted on the machine frame at 9. On the arms 8, which are mounted on the upper end of the lever 10, there is provided an axle 11 on which a support 12 is rigidly mounted for movable tong jaws 13 which consist of two plates attached to the support 12, each of which plates has two lugs 13' which project in the corresponding operative position into the range of the recesses 1' of the table 1. On the axle 11 there is firmly mounted a control lever 14, the end of which is provided with a roller 15, adapted to co-operate with a plate 17 mounted on the machine frame at 16, which plate, when in its neutral position, rests on a pin 18 provided on the machine frame.

When the lever 10 swings to the right as indicated in Figs. 1 and 6, the roller comes into contact with the plate 17. This causes the lever 14 and the jaws 13 connected therewith to swing out against the tension of a spring 19 in such manner that the mouth of the tongs opens. When the lever 10 has arrived in its extreme right-hand position in which, as shown particularly in Fig. 4, the front edge of the wrapper U comes into position between the opened mouth of the tongs, the roller 15 on the lever 14 comes into the range of a recess 17' provided in the plate 17. The roller on the lever 14 is thereby released and is able to swing into the position indicated in full lines in Fig. 7. At the same time the wrapper is held firmly, under the action of the spring 19, between the jaws 13' and 7 of the tongs. When the lever 10 swings back into the position indicated in Fig. 2, the wrapper is carried along and withdrawn on to the depositing

table which is subjected to moderate suction action, the wrapper at the same time is tightened and smoothed (see Fig. 5). When the lever 10 swings back into the position indicated in Fig. 7, 5 the roller 15 comes into contact with the bottom side of the plate 17, because the plate is moved correspondingly upwards.

When the lever 10 swings back, the wrapper is passed over the rolling apron 20, the latter being attached, in known manner, on one side to the rolling table 22 at 21. On the other side the rolling apron is passed over the roller 23 and is attached to the roller 24 flexibly if desired. The known trough in the rolling table is formed on the 10 one hand by a jaw 25 which is carried by a tubular member 26 provided with a collar 26'. Into the tubular member 26, which is adapted to be displaced axially in a housing 27 attached to the machine frame G, there is passed a rod 28. 15 A sleeve 29 is pivotally mounted on the rod 28, and with this a lever 30, which is pivotally mounted on the machine frame at 31, engages. The lever 30 is provided with a roller 32 which comes into contact with a cam disc 33. The 20 cam disc is mounted on a shaft 34 to which a spur wheel 35 is also attached. The spur wheel 35 engages with a corresponding spur wheel 36 which is mounted on the driving shaft 37 of the machine, this shaft 37 being connected by means 25 of a belt pulley 38 and a driving belt 39, with the electro-motor 6. On the driving shaft 37 is mounted a crank disc 40, the crank pin 41 of which engages in a cam slot 10' of the lever 10. The other side of the trough is formed 30 by a plate 42, which is pivotally mounted on an axle 43, which is provided on the horizontal part of the jaw 25. An arm 42' of the plate 42 protrudes into a recess in the jaw 25 and is pressed by a spring 44 against the head 28' of the rod 28. 35 When the tongs 7, 13 have arrived in the position indicated in Fig. 8, the rolling table trough 25, 42 is brought into the position indicated in Fig. 8. This is effected by means of the lever 30, in that, between the upper adjusting nuts 29' 40 of the sleeve 29 and the collar 26' of the tubular member 26, a spring 45 is inserted. The tubular member 26 and the jaws 25 connected therewith are therefore upwardly displaced by the lever 30 without the rod 28 being displaced 45 in the tubular member 26 until the collar 26' rests against the bottom of the housing 27. In this position a spring-controlled stop 47 which is provided in a pressure chamber 48 is pressed back in such manner that it is placed flexibly on, and thereby firmly holds, the wrapper U located on the rolling apron 20. But at the same 50 time a projection 14' provided on the lever 14 strikes against a stop consisting of an adjusting screw 49 whereby the mouth of the tongs is 55 opened so that the wrapper now lies freely on the rolling apron 20, held only by the flexible pressure member 47. Now while the plunger 50 thrusts the compressed tobacco P from the pressure chamber 48, the sleeve 29 is raised owing 60 to its further movement into the position indicated in Fig. 9. As the tubular member 26 and the jaws 25 have attained their highest position the further movement of the lever 30 is 65 utilized, while overcoming the spring 45, to displace the rod 28 upwardly in the tubular member 26. This causes the plate 42 to be moved 70 outwards so that the filler can be introduced without difficulty. During this operation, the 75 spring-controlled pressure member 47 holds the

wrapper firmly so that it cannot slip when the filler is introduced.

As soon as the plunger 50 has returned to its upper position, the lever 30 is guided downwards by the cam disc 33 which first of all causes the 5 plate 42 to move inwardly (see Fig. 10). Then the trough consisting of the jaws 25 and the plate 42 is moved downwards again so that the rolling apron passed over the upper surface of the jaw 25 rests on the rolling table 22. Then the 10 lever 10 is swung to the right as indicated in Fig. 2, whereby a roller 51 mounted on the lever 10 comes into engagement with the rolling apron 20 in such manner that the bunch is in a loop formed behind the roller 51. Fig. 11 shows 15 the precise moment in the operation when the filler P which is for the greater part covered by the wrapper, is withdrawn from the trough, which is done by a slight movement of the plate 42. By this means the corresponding end of the 20 wrapper is placed firmly about the filler P. As soon as the bunch formed in this manner has reached the end of the rolling table, it is deposited in known manner in a receiving trough 25 or the like. These receiving troughs may be attached to a conveyor chain which feeds the bunch forward to the place where it receives further treatment, for instance to the rolling device in which the wrapper is applied. In its extreme 30 right-hand position the roller 15 of the movable 35 tong jaws comes into contact with the plate 17 so that when it swings into its extreme outermost position, the tongs with open jaws come into the range of the depositing table 1 whereupon 35 the operation is repeated.

Having thus described the nature of the said invention and the best means I know of carrying the same into practical effect, I claim:—

1. In a cigar bunching apparatus, the combination of a rolling table, an apron associated with said rolling table, a roller cooperating with said apron, means moving said roller to and fro above said table, a wrapper support, means for gripping an end of a wrapper upon said support while leaving a portion of said wrapper free and means for moving said wrapper from said support whereby said wrapper is smoothed. 40

2. In a cigar bunching apparatus, the combination of a rolling table, an apron associated with said rolling table, a roller cooperating with said apron, means moving said roller to and fro above said table, a wrapper support, means for gripping an end of a wrapper while the wrapper is entirely upon said support while leaving a portion of said wrapper free, means for moving said 50 wrapper from said support to the right in said apron and then releasing said wrapper. 55

3. In a cigar bunching apparatus, the combination of a rolling table, an apron associated with said rolling table, a roller cooperating with said apron, means moving said roller to and fro above said table, a fixed wrapper support, mechanical means for gripping an end of a wrapper upon said support while leaving a portion of said 60 wrapper free and means for moving said wrapper from said support whereby said free portion of said wrapper is smoothed. 65

4. In a cigar bunching apparatus, the combination of a rolling table, an apron associated with said rolling table, a roller cooperating with said 70 apron, means moving said roller to and fro above said table, a wrapper support, means for gripping an end of a wrapper upon said support while leaving a portion of said wrapper free, means for moving said 75 wrapper from said support and pneu- 75

matic means acting upon said free portion of said wrapper whereby said wrapper is smoothed.

5. In a cigar bunching apparatus, the combination of a rolling table, an apron associated with 5 said rolling table, a roller cooperating with said apron, means moving said roller to and fro above said table, a wrapper support, means for gripping an end of a wrapper upon said support while leaving a portion of said wrapper free, means for 10 moving said wrapper from said support and pneumatic means operative through said support acting upon said free portion of said wrapper whereby said wrapper is smoothed.

6. In a cigar bunching apparatus the combination of a rolling table, an apron associated with 15 said rolling table, a roller cooperating with said apron, means moving said roller to and fro above said table, a wrapper support, means upon said moving means for said roller for gripping a wrapper upon said support and moving the same over the bight in said apron and then releasing said wrapper and means for operating said last named means.

7. In a cigar bunching apparatus, the combination of a rolling table, an apron associated with 25 said rolling table, a roller cooperating with said apron, means moving said roller to and fro above said table, a wrapper support, means mounted upon said moving means for said roller for 30 moving a wrapper from said wrapper support over the bight in said apron and means associated with said last named means operable by the motion of said moving means for said roller for gripping said wrapper.

35 8. In a cigar bunching apparatus the combination of a rolling table, an apron associated with said rolling table, a roller cooperating with said apron, means moving said roller to and fro above said table, a wrapper support, means upon said 40 moving means for said roller for moving a wrapper from said support over the bight in said apron and automatically operating grippers for said wrapper carried by said last named means for gripping said wrapper and releasing said wrapper when over the bight in said apron.

45 9. In a cigar bunching apparatus the combination of a rolling table, an apron associated with said rolling table, a roller cooperating with said apron, means moving said roller to and fro above 50 said table, a wrapper support, means for gripping a wrapper upon said support and moving the same over the bight in said apron and means associated with said support for smoothing said wrapper as the same is moved thereacross.

55 10. In a cigar bunching apparatus the combination of a rolling table, an apron associated with said rolling table, a roller cooperating with said apron, means moving said roller to and fro above said table, a wrapper support, means for gripping 60 a wrapper upon said support and moving the same over the bight in said apron and pneumatic means associated with said support for smoothing said wrapper as it is withdrawn from said support.

65 11. In a cigar bunching apparatus the combination of means for bunching cigar fillers, a support for a wrapper for said fillers, means for removing a wrapper from said support, means for smoothing said wrapper as the same is being removed and means for associating the same with 70 the filler operated upon by said bunching means.

75 12. In a cigar bunching apparatus the combination of means for bunching cigars, a support for a wrapper, means for gripping a wrapper while the same is resting entirely on said support and removing said wrapper from said support and

associating the same with the filler operated upon by said bunching means and means associated with said support for smoothing said wrapper as said wrapper is withdrawn from said support.

5 13. In a cigar bunching apparatus the combination of means for bunching cigars, a support for a wrapper, means for removing a wrapper from said support and associating the same with the filler operated upon by said bunching means and pneumatic means associated with said support for smoothing said wrapper as the same is removed from said support by said removing means.

10 14. In a cigar bunching apparatus the combination of a rolling table, an apron associated with said rolling table, a roller cooperating with said apron, pivoted means upon which said roller is mounted for oscillating said roller above said table, a wrapper support, mechanical gripping means carried by said pivoted means for gripping 15 a wrapper upon said support and moving the same over the bight in said apron and then releasing said wrapper and means for operating said mechanical gripping means.

15 15. In a cigar bunching apparatus the combination of a rolling table, an apron associated with said rolling table, a roller cooperating with said apron, pivoted levers upon which said roller is mounted for moving said roller to and fro above 20 said table, a wrapper support, a gripper mounted upon said pivoted levers for gripping a wrapper while the same is entirely upon said wrapper support and cam means for operating said gripper so as to grip a wrapper upon said wrapper support.

25 16. In a cigar bunching apparatus the combination of a rolling table, an apron associated with said rolling table, a bunching roller cooperating with said apron, oscillating means upon which said bunching roller is mounted, a fixed gripping 30 bar upon said oscillating means, a bell-crank lever upon said oscillating means and gripping fingers carried by said bell-crank lever cooperating with said fixed bar for gripping wrappers.

35 17. In a cigar bunching apparatus the combination of a rolling table, an apron associated with said rolling table, a roller cooperating with said apron, oscillating means for moving said roller to and fro above said table, a wrapper support, a fixed gripping bar carried by said oscillating 40 means, a bell-crank lever also carried by said oscillating means, gripping fingers mounted upon said bell-crank lever cooperating with said gripping bar, a roller mounted upon the free end of said bell-crank lever and a fixed pivoted plate 45 cooperating with said roller so as to operate said gripping fingers upon the movement of said oscillating means to and fro.

50 18. In a cigar bunching apparatus the combination of a rolling table, an apron associated with said rolling table, a roller cooperating with said apron, reciprocating means for moving said roller to and fro above said table, a wrapper support, a fixed gripping bar carried by said reciprocating 55 means, pivoted gripping fingers also carried by said reciprocating means cooperating with said bar for gripping a wrapper and means operated by the motion of said reciprocating means for opening and closing said gripping means.

60 19. In a cigar bunching apparatus the combination of a rolling table, an apron associated with said rolling table, a roller cooperating with said apron, oscillating means moving said roller to and fro above said table, a wrapper support, pneumatic means for holding a wrapper upon said 65

- wrapper support, a fixed gripping bar upon said oscillating means, pivoted gripping fingers also mounted upon said oscillating means, spring means normally holding said gripping fingers in contact with said bar and means operable by the motion of said oscillating means for opening and closing said gripping means.
20. In a cigar bunching apparatus the combination of a rolling table, an apron associated with said rolling table, a roller cooperating with said apron, means for moving said roller to and fro above said table, gripping means for a wrapper carried upon said moving means and a pivoted plate mounted upon said rolling table cooperating with said grippers for mechanically actuating the same.
21. In a cigar bunching apparatus the combination of a rolling table, an apron associated with said rolling table, a roller cooperating with said apron, oscillating means moving said roller above said table, a fixed gripping bar upon said oscillating means, pivoted gripping fingers cooperating with said bar to grip a wrapper and move the same over the bight in said apron, a pivoted plate upon said rolling table for pivoting said gripping fingers at one terminal of the oscillating means and an adjustable stop for operating the gripping fingers at the other terminal of said oscillating means.
22. In a cigar bunching apparatus the combination of a rolling table, an apron associated with said rolling table, a roller cooperating with said apron, a filler trough positioned below said apron, means for reciprocating said filler trough, oscillating means for moving said roller to and fro above said table, gripping means carried by said oscillating means for moving a wrapper above said trough and resilient means cooperating with said trough for holding said wrapper above said trough.
23. In a cigar bunching apparatus the combination of a rolling table, an apron associated with said rolling table, a roller cooperating with said apron, oscillating means for moving said roller above said table, a filler trough located below said apron, means for moving said trough above said rolling table and resilient means cooperating with said trough for maintaining a wrapper positioned over said trough.
24. In a cigar bunching apparatus the combination of a rolling table, an apron associated with said rolling table, a roller cooperating with said apron, oscillating means for moving said roller to and fro above said table, a filler trough positioned adjacent said rolling table, a pivoted wall upon said trough, means for moving said trough above said rolling table and means for pivoting said pivoted wall of said trough when said trough is in uppermost position.
25. In a cigar bunching apparatus the combination of a rolling table, an apron associated with said rolling table, a roller cooperating with said apron, oscillating means for moving said roller to and fro above said table, mechanically operated gripping means mounted upon said oscillating means for gripping and moving a wrapper over the bight of said apron, means for smoothing said wrapper and means for holding
- said wrapper above the bight in said apron when released by said gripping means.
26. In a cigar bunching apparatus the combination of a rolling table, a bunching roller co-operating with said apron, a support for said bunching roller swinging between two spaced points, gripping means carried by said support and means for opening said gripping means at said spaced points.
27. In a cigar bunching apparatus the combination of a rolling table, an apron associated with said rolling table, a bunching roller, a support for said bunching roller swinging between two spaced points, a wrapper table located adjacent one of said points, grippers carried by said support and means for opening said grippers as the support swings towards said wrapper table.
28. In a cigar bunching apparatus the combination of a rolling table, an apron associated with said table, a bunching roller cooperating with said apron, a support for said bunching roller swinging between two spaced points, a wrapper table located adjacent one of said points having recesses therein, grippers mounted upon said support spaced thereon so as to come opposite said recesses and means for operating said grippers.
29. In a cigar bunching apparatus the combination of a rolling table, an apron associated with said rolling table, a roller cooperating with said apron, means moving said roller to and fro above said table, a wrapper support, automatic means for gripping a wrapper upon said support and moving the same over the bight in said apron and then releasing said wrapper, a trough associated with said rolling table, means for raising said trough to the ejection opening of a pressure chamber and means for lowering said trough in synchronism with said moving means of said roller.
30. In a cigar bunching apparatus as claimed in claim 29 in which one wall of the trough is formed as a spring control pivoted member.
31. In a cigar bunching apparatus, a pressure chamber for compressing fillers for cigars, a rolling table located beneath said pressure chamber, a trough adjacent said rolling table for receiving the fillers from said pressure chamber and spring controlled clamping means upon said pressure chamber for holding a wrapper over said trough.
32. In a cigar bunching apparatus the combination of a rolling table, an apron associated with said rolling table, a roller cooperating with said apron, means oscillating said roller above said table, a pneumatic wrapper support and automatic gripping means for mechanically gripping the side of a wrapper upon said support and moving the same over the bight in said apron and then releasing said wrapper.
33. In a cigar bunching apparatus the combination of means for bunching a filler, a wrapper support, means for transferring a wrapper from said support to said bunching means and means for smoothing said wrapper automatically as it is drawn from said support prior to its association with said filler.

FRANZ HEINRICH BENNO STELZER.
